ADJUSTABLE DIAL ANGLE METER

Frank A. Nowak, 3550 Flower St.,
Santa Maria, Calif. 93454

Filed June 29, 1972, Ser. No. 267,430

Term of patent 14 years

Int. Cl. D10—04

U.S. Cl. D52—6 R

FIG. 2

FIG. 1

FIG. 3

FIG. 1 is a top plan view of an adjustable dial angle meter showing my new design; the bottom thereof being plain and unornamented;

FIG. 2 is a left side elevational view thereof;

FIG. 3 is an end elevational view thereof.

I claim:

The ornamental design for an adjustable dial angle meter, as shown and described.
